(No Model.)

D. N. GLEASON.
ELECTRIC FUSIBLE CUT-OUT.

No. 546,613.

Patented Sept. 17, 1895.

UNITED STATES PATENT OFFICE.

DUANE N. GLEASON, OF BROOKLYN, NEW YORK.

ELECTRIC FUSIBLE CUT-OUT.

SPECIFICATION forming part of Letters Patent No. 546,613, dated September 17, 1895.

Application filed July 19, 1892. Serial No. 440,557. (No model.)

To all whom it may concern:

Be it known that I, DUANE N. GLEASON, a citizen of the United States, and a resident of Brooklyn, in the county of Kings and State 5 of New York, have invented certain new and useful Improvements in Electric Fusible Cut-Outs, of which the following is a specification.

My invention relates to improvements in 10 electric fusible cut-outs.

The objects of my improvements are to secure more certainty in its proper operation by providing means whereby an interruption of the current will take place upon the destruction 15 of the fusible conductor by an overcharge of electricity, to simplify the construction, and to enable the cut-out to be repaired with facility.

Figure 1 is a top view of the fusible cut-out. Fig. 2 is a side view partly in section. Fig. 3 is a sectional side view of a modification. Fig. 4 is a section on line 1 2, Fig. 1.

The base A is formed of some non-conducting material. Contact-pieces B C, each being 25 U-shaped, having arms b b and c c, respectively embrace, the part a of the base A, and may be caused to retain their position by being fitted closely to the base, or the screws that hold the conductor may pass through the 30 arms and through perforations in the base, as in Fig. 3. This method of construction does away with the necessity for attaching the contact-pieces to the base by means of separate screws, saving the cost of the screws and 35 of cutting a thread in the base.

G is an electric-line conductor making contact with B. G' is an electric-line conductor making contact with C.

H is the fusible electric conductor connecting 40 the electric conductors G and G' by means of the U-shaped contact-pieces B C.

Through the base A, between the contact pieces B C, an opening a' is made, across or through which the fusible electric conductor 45 extends. The object of the opening is to afford more space for the fused metal of the conductor H between the contact-pieces, so that after fusion there will be little or no liability of the passage of the current. This is 50 accomplished without enlarging the external proportions of the cut-out. The additional room gained between the contact-pieces per-

mits a fusible conductor of a greater length to be used.

By the use of the two-armed contact-pieces 55 I am enabled to secure the advantage of permanent connections between the main-line conductors G and G' with the contact-pieces B C, as the screws D E need not be disturbed when a new fusible conductor is to be inserted. The fusible conductor connects with the contact-pieces by means of the screws J K, Fig. 2, at the arms opposite to those connecting with the conductors G G'. This permits renewal of the fusible conductor without 60 disturbing the connections of the conductors G G', the repairing being done with great facility.

Fig. 3 shows a modification wherein the screws L M are placed on opposite sides of 70 the base A, the contact-pieces being arranged with the part connecting the two arms extending through the opening a'. The fusible conductor passes through the opening a', one end making contact on one face of the base 75 A, and the other end making contact on the opposite face. In this modification the conductors G G' are connected by means of the screws L M, and the fusible conductor is connected by nuts N N upon the screws. These 80 nuts can be removed without disturbing the screws. It will be observed that the flange extends all around the block to prevent contact with any of the surrounding parts.

What I claim is—

85

1. In an electric cut out, the combination with an insulating base having an opening through it, of U-shaped contact pieces, forming two arms, connecting screws on one side of the base, and connecting nuts on the opposite side for attaching the line conductor and fusible conductor, respectively, the fusible conductor extending through and across said opening, substantially as specified.

90

2. In an electric cut out, the combination 95 of a base composed of non-conducting material having an opening through it; a fusible conductor extending across the opening and contact pieces embracing both sides of the base, substantially as specified.

100

3. An electric cut out, consisting of a base of insulating material, having contact pieces at each end, embracing both sides of said base, an opening through the base and a fusible

conductor extending through and across the opening connecting the contact pieces, substantially as specified.

4. In an electric cut out the combination of U-shaped contact pieces, one arm of which extends above, and one below the insulating base; with screws for connecting the electrical conductors and nuts, secured to the screws for connecting the fuse to the contact pieces, substantially as set forth.

5. In an electric cut out, the combination of U-shaped contact pieces one arm of which extends above and one below the insulating base; with screws for connecting the electrical conductors, and nuts, secured to the screws adjacent to the contact pieces, for connecting the fuse to the contact pieces, substantially as set forth.

6. In an electric cut-out, the combination of U-shaped contact pieces, one arm of which extends above, and one below the insulating base; with screws for connecting the electrical

conductors and nuts, secured to the screws adjacent to the contact pieces, and on the outside of the contact pieces, for connecting the fuse to the contact pieces, substantially as set forth.

7. In an electric cut-out, the combination of U-shaped contact pieces, one arm of which extends above, and one below the insulating base; with screws for connecting the electrical conductors, and nuts, secured to the screws on the side of the insulating base, opposite the side at which the head of the screw is located, for connecting the fuse to the contact pieces, substantially as set forth.

Signed at New York, in the county of New York and State of New York, this 16th day of May, A. D. 1892.

DUANE N. GLEASON.
